FLOOR BOX

Filed Sept. 24, 1920

UNITED STATES PATENT OFFICE.

HAROLD G. BAXTER, OF BALDWIN, NEW YORK, ASSIGNOR TO WESTINGHOUSE ELECTRIC & MANUFACTURING COMPANY, A CORPORATION OF PENNSYLVANIA.

FLOOR BOX.

Application filed September 24, 1920. Serial No. 412,559.

My invention relates to floor boxes and particularly to the terminal boxes commonly employed in housing electrical outlets placed in floors of buildings.

5 An object of my invention is to provide a floor-box construction wherein the crown or cover member may be so permanently attached to the box that its upper face is flush with the floor regardless of misalignment of the box and its elevation with respect to the level of the floor.

Another object is to provide a box construction having the above characteristics wherein an adjustable support is provided 15 for supporting the cover or crown in proper position with respect to the floor and which may be removed after the sealing or cementing agent has been applied or has hardened.

20 A further object is to provide a box construction wherein the supporting member for supporting the crown member during the grouting operation serves to close the space between the members and prevent the escape of the plastic or liquid cementing agent.

25 Heretofore, boxes have been made with an annular groove in their upper edge adapted to receive an annular tongue projecting downwardly from the crown member. The space between the tongue and the walls of 30 the groove is filled with a cementitious material which is usually applied in a plastic or liquid state and which subsequently hardens.

In such devices, the crown is supported by 35 the annular tongue which engages the bottom of the groove and, consequently, if the box is located permanently in a tilted position, or in a position beneath the proper elevation thereof with respect to the floor, the crown 40 or cover is supported in a correspondingly misplaced position with respect to the floor level. It is very difficult to so properly position the box that the crown will be flush with the floor level when supported upon the 45 box, and an object of my invention is to obviate this difficulty by providing an adjustable support for the crown which may be so adjusted that, when the crown is supported thereon, the top face of the box is flush with 50 the floor level.

These and other objects that will be made apparent throughout the further description of the invention are attained by means of the floor-box construction herein described and

illustrated in the accompanying drawings, 55 wherein:—

Figure 1 is a plan view showing the improved box construction; and

Fig. 2 is a vertical section on the line II—II of Fig. 1. 60

Referring to the drawing, the apparatus includes a cylindrical box member 3 having a closed bottom 4 and outlets 5 (one of which is shown) through which the conductor terminals (not shown) enter the box. The 65 usual practice is to secure the box to the conductor conduit which serves to support the box in a permanent position in which the box registers with a suitable opening provided in the floor and wherein the top of the 70 box is positioned a short distance beneath the floor level.

The upper portion of the box is provided with exterior annular ridges 6, and a cylindrical cover or crown 7 is telescoped over the 75 ridged portion and is provided with interior annular ridges 8 corresponding with those on the box. As the crown member telescopes loosely over the box member, sufficient space is provided therebetween to permit universal 80 adjustment of the cover with respect to the box. That is, the longitudinal axes of the box and cover may be disposed at an angle to one another or the crown may be adjusted longitudinally of the box. The crown member is 85 open at both ends and is provided with inwardly-directed lugs 9 that are tapped to receive the screws 10 which serve to secure the cap 11 to the crown.

The interior of the box is provided with a 90 bracket 12 upon which any standard form of plug receptacle may be mounted, such, for instance, as the receptacle 13 that is adapted to receive a plug 14. The cap 11 is provided with a bell-shaped housing that may be 95 screwed on or off the cap when adjusting the plug. The crown 7 is permanently secured to the box 3 after the box has been permanently located in the floor structure, by means of a hardening material, such as cement 16 that 100 is applied to the space between the box and the cover while in a plastic or semi-liquid state. During the cementing operation, an elastic band 17, preferably made of rubber and having a circular cross-section, is slipped 105 over the housing and so adjusted thereon that, when the cover is supported thereupon and is in contact with the band throughout the

- entire periphery of the lower end thereof, the top face of the crown or cover is flush with the floor level. The band serves as a supporting member and as a sealing member for so closing the lower end of the space between the box and crown member that the cementitious material is retained while it is being applied at the upper edge of the box member through the opening in the crown member. After the cement has been grouted in the space between the box and crown members and has hardened, the band 17 may be removed for reuse by so expanding it that it may be slipped upwardly over the crown member.
- 15 The construction is extremely simple and the elastic band used for supporting the crown member may be used a number of times. While I have specifically described a band made of rubber, it is obvious that other adjustable means may be employed for supporting the cap in any relative position with respect to the box.
- 20 While I have described and illustrated but one embodiment of my invention, it will be

apparent to those skilled in the art that various changes, modifications, additions, substitutions, and omissions may be made in the apparatus described without departing from the spirit and scope of the invention, as set forth by the appended claim.

30

I claim as my invention:

The combination with a floor-box member and a crown member therefor loosely telescoping over the box member and adjustable with respect thereto and adapted to be permanently retained in adjusted position by a hardening agent disposed between the telescoped sections of the members, of an expandible band adjustably mounted upon the box member for supporting the crown member and closing the space between it and the other member while the said agent is being applied and adapted to be expanded for removal over the said crown member.

35

In testimony whereof, I have hereunto subscribed my name this seventeenth day of September, 1920.

40

HAROLD G. BAXTER.
